UNITED STATES PATENT OFFICE.

EDWIN JOHN SIBLEY, OF JAMAICA, NEW YORK.

FRICITION ADJUSTER.

Application filed November 10, 1921. Serial No. 514,205.

To all whom it may concern:

Be it known that I, EDWIN JOHN SIBLEY, citizen of Canada, and resident of Jamaica, in the county of Queens and State of New 5 York, have invented certain new and useful Improvements in Friction Adjusters, of which the following is a specification.

This invention relates to friction adjusters for use on casement windows, transoms, 10 doors or any other hinged device the free swing of which it is desired to control.

One object of the invention is to provide means whereby the degree of frictional resistance in the adjuster may be regulated or 15 adjusted to a fine degree by simply grasping the barrel of the adjuster in the hand and rotate it either to the left or to the right until the frictional resistance has been regulated as may be desired.

20 Another object of the invention is to provide means whereby complete release from frictional resistance is given to the hinged device as it reaches approximate closing position. That is to say, the invention has for 25 one of its objects the provision of certain novel features of construction designed to give to the hinged device absolute freedom from resistance in the adjuster at the moment or time of closing, so that there 30 will be no torsion or strain caused by actual closing (or opening) tending to hinder or prevent the free operation of the adjuster.

In the majority of cases the friction adjuster is used at the top of the casement 35 window, while the pull in closing is more often at the bottom or lower half of the frame. Hence it will be readily understood that under such conditions, the resistance against the window operates at the top there- 40 of or outward, while in the act of closing there is a force acting directly opposite or inward. A torsional twisting or spring in the frame immediately results from this condition, so that although the window may be 45 tightly closed at the bottom against the frame, the outward thrust of the adjuster at the top prevents the window from fitting tightly into the frame along its whole length, with the result that it becomes difficult to 50 operate the bolt or fastener usually employed, and complete closing of the window is not obtained.

55 This invention provides means permitting free operation, that is closing of the window, the same as if no adjuster were used.

In accordance with the above and other

objects for the purpose of providing a generally improved friction casement adjuster, the invention comprises such features of construction and arrangements of parts as are 60 hereinafter set forth and as illustrated in the accompanying drawing in which—

Fig. 1 is a view of my improved casement adjuster, partly in section and with parts 65 broken away.

Fig. 2 is a transverse sectional view on line 2—2 of Figure 1.

Fig. 3 is a longitudinal sectional view on line 3—3 of Figure 1.

Fig. 4 shows the arrangement of the bolt 70 or fastener for pivoting the adjuster to the frame looking in the direction of arrow 4 in Figure 3.

Fig. 5 is a view similar to Figure 4 illustrating the relative sliding movement between the fastening bolt in the frame and 75 the adjuster.

Fig. 6 is a similar view but shows the parts in a different position.

The casement adjuster comprises a barrel 80 1 which is rotatably mounted as at 2 on a head or arm 3 secured to a bolt 4 by screw threads 5 and a pin 6 driven through the arm 3 and the bolt 4. The numeral 7 denotes the window sill, frame or other fixed 85 member enclosing the window sash 8 or other movable member, the free swing of which it is desired to control. The sash 8 is pivoted to the frame 7 by hinges as at 9.

To the movable member 8 is secured a 90 bracket 10 to which is pivoted at 11 a plunger 12. A cap 13 on the end of the barrel provides a guiding means for the plunger and serves also to close the end of the 95 barrel and enhances the appearance of the device.

The barrel 1 and the plunger 12 are operatively connected by a suitable clutch or friction device providing the required frictional resistance between the two members. 100 Within the barrel the plunger is provided with a reduced threaded portion 14 or screw having a pointed head 15 adapted to operate between two springs 16, 16 seated in the clutch members, 17, 17. These latter are symmetrical and of suitable friction material, and each member is formed with a recess 18 for receiving the spring 16 and a reduced bearing portion 19 for the screw 14. In addition each friction member has a nut receiving recess 20. 21 is a nut in threaded engagement with the screw 14. The clutch 105 110

members 17 are substantially semicircular in cross section as seen in Figure 2.

In assembling the device, the springs are laid in the recesses 18, the nut 21 is placed

5 in the recesses 20 and thus assembled the clutch is pushed inside the barrel 1 in which the clutch slides with a nice fit. Thereafter the plunger is screwed into the nut until the pointed head 15 engages the springs and 10 separates them, thus putting tension on the clutch members in forcing them outward against the wall of the barrel. The cap has of course first been placed on the plunger and is thereafter screwed fast in the barrel.

15 In order to prevent the torsion or twist of the sash, which has been described above, I provide relative sliding movement between the adjuster and the bolt 4 as follows:

The bolt 4 is provided with a head 25 20 having two diametrically disposed notches 26, 26. The bolt is slidably and rotatably mounted on a base 27 provided with an opening 28 in which said bolt operates. The base 27 forms a recess 29 for the bolt head 25 and in said base and recess there is secured in any suitable manner a key or stop 30. The base is secured to the sill 7 by screws 31.

In closed position the parts assume the 30 position shown in Figures 3 and 4, in which it will be observed that the bolt 4 is at the one side of the opening 28, which may be considered as being a circular slot, and the bolt is locked against rotative movement by 35 the key 30 which engages one of the notches 26. When it is desired to open the window, the force is applied adjacent the free swinging side of the window or at the point 35 in Figure 1. The moment force is applied 40 at said point, the bolt 4 is moved within the opening 28 from the position shown in Figure 4 to the position shown in Figure 5, in which the bolt 4 is unlocked from the key 30 and free to rotate. Continuing the application 45 of force at the point 35 the window may be opened as seen in Figure 6 which shows the bolt 4 turned on its axis as the window is opened. In other words, the opening of the window causes first a sliding movement 50 of the bolt, which sliding movement naturally and almost at once is merged into the turning movement of the bolt as the window is opened.

55 After the window is opened, the friction is adjusted by merely grasping the barrel 1 with one hand and rotate it either to the left or to the right and without necessitating operation of any other part. The rotation of the barrel causes the plunger to be screwed 60 into or out of the nut 21 to force the springs apart to increase the friction, or to permit the springs to relax to decrease the friction or tension of the springs. The adjustment 65 of the friction is preferably done when the window is open as it then is easy to deter-

mine the degree of frictional resistance required to hold the window in the position desired or to withstand a certain local wind pressure.

The advantages of the slideable pivot 4 70 are more apparent and important in closing the window.

As explained above, when the window is almost closed or within, say one inch of closing, there is an outward thrust by the 75 adjuster operating against the inwardly acting force tending to close the window. The nearer the window comes to closing position, the greater is the difference between the two said forces operating in opposite directions. Without the sliding pivot 4, the closing of the window causes a torsion or strain, which prevents free turning movement of the bolt 4 and consequently prevents complete easy closing of the window. 80

In this case, however, it will be seen that when the window is about to close completely, the bolt 4 moves easily from the position shown in Figure 6 to the position shown in Figure 5, from whence the bolt 90 continues its movement "home" into locked position as in Figure 4. In other words, the bolt 4 is during the last small movement (in closing) completely freed from any torsion 95 or strain and the outward thrust at the point 35 opposing the closing movement is eliminated.

The construction herein disclosed possesses many advantages. And the larger 100 the window, door or transom, to which the adjuster is employed, the more important these advantages appear. Adjustment is obtained to a very fine degree without using any tools or detaching any parts, and complete easy closing and opening is obtained by reason of the, however slight, sliding movement of the bolt 4 set forth. 105

The bolt head 25 is provided with two notches 26 as a matter of convenience. The notches may be used with a spanner to screw the bolt into the arm 3 and the presence of two notches makes it easy to adjust the bolt head so that one notch will be in proper position with respect to the key 30 as will be understood. 110

115 Adjusters constructed as herein set forth are adapted for use with swinging members of all sizes and dimensions. They may be adjusted to hold a very large transom, door or window against relatively very strong pressure. Yet, if such pressure should be unexpectedly and suddenly exceeded, the entire friction device will yield and slide within the barrel thus preventing breaks. 120

125 While I have shown my invention in its preferred form, changes may of course be made within the principle of the invention and the scope of the appended claims.

I claim:

130 1. The combination with a window casing

- and a window hinged thereto, of two interconnected telescopic members, frictional means interposed between the latter, means for pivoting one of said telescopic members 5 to the said window, mechanism for pivoting the other of said telescopic members to the said window casing in a manner to impart unopposed sliding movement to the said two members at the opening and closing of the 10 said window, said mechanism comprising a base secured to said window casing, a pivot on said other telescopic member arranged to rotate in said base member in two opposed directions and capable of a sliding movement 15 with respect to said base at the beginning of the rotative movement in one direction and at the end of the rotative movement in the other direction.
2. The combination with a window casing 20 and a window hinged thereto, of two telescopic members, one of which is pivoted on said window, the other of which is pivoted on said window casing, means for operating said two telescopic members in frictional relationship while the said window moves with respect to the said window casing and means for automatically eliminating resistance to the operation of said telescopic members when the window is opened or closed.
3. The combination with a swinging window and its frame, of a friction adjuster comprising a plunger pivoted on said window, a barrel for said plunger pivoted on the window frame, friction means between 35 said plunger and barrel and means permitting said barrel to slide longitudinally of its axis with respect to the said window frame at the opening and closing moments of said swinging window whereby to eliminate torsional strains in said adjuster at the opening and closing moments aforesaid.
4. A friction adjuster comprising two telescopic members, friction means between the same, means for pivotally connecting one of 45 said members to a fixed element, said pivotal means comprising a base plate having an opening, a pivot secured to the said one member and mounted to rotate and slide within the said opening and means in said base 50 plate for preventing rotation of said pivot at predetermined stages during the operation of the said friction adjuster.
5. A pivotal connection for friction adjusters having two frictionally operated interconnected telescopic members, comprising a base having an opening, a pivot bolt in one of said members arranged to rotate and slide within said opening and means for automatically locking the said one member against 55 rotation.
6. A pivotal connection for friction adjusters having two frictionally operated interconnected telescopic members comprising a base having an opening, a pivot bolt secured in fixed relationship to one of the said telescopic members and arranged to rotate and slide within said opening, a notched head on said pivot bolt and a key secured to the said base and adapted to engage a notch in the said head to lock the said one telescopic member against rotation. 65
7. A casement window adjuster comprising two telescopic members, means for pivoting the one member to the window, mechanism for securing the other member to the window casing in slidable and rotatable relation thereto whereby to eliminate resistance to the operation of said adjuster when the window is opened or closed. 75
8. A casement window adjuster comprising two telescopic members, friction means between the same, means for pivoting one of said members on the window, mechanism for securing the other of said members to the window casing, and means in said mechanism for relieving the same of resistance from said friction means when the window is opened or closed. 80
9. A casement window adjuster comprising two telescopic members, means for pivoting the one member to the window, mechanism for securing the other member to the window casing comprising a base secured to the window casing and a slidable and rotatable connection between said base and said other member whereby lateral movement free from torsional strains is imparted to said adjuster at the opening and closing of the said window. 90
10. A casement window adjuster comprising two telescopic frictionally engaged members, means for pivoting the one member to the window and mechanism for securing the other member to the window casing in a manner to impart an unopposed sliding movement to said adjuster when said window is opened or closed. 105
11. In a casement window friction adjuster, mechanism giving the window absolute freedom from resistance in the adjuster at the moment of closing said window, said mechanism comprising a member pivoted to the window, a second member, friction means between said two members and a pivotal connection between said second member and the window casing permitting slid- 110 able and rotatable movement between said second member and the window casing at the time the window is being closed.

EDWIN JOHN SIBLEY.
